LOOSELEAF BINDER

Norman L. Huffaker, 5400 Bawley Road,
Richmond, Va. 23226
Filed May 9, 1966, Ser. No. 548,644
1 Claim. (Cl. 129—24)

This invention relates to improvements in looseleaf binders of the character used for holding punched sheets.

Looseleaf binders of the character used heretofore, constructed with rings to receive thereon multiple punched sheets, either for holding a stack of sheets of equal size, or multiple punched visible sheets, have been expensive in construction, due to the complexity thereof or the size of the rings and the operation of the latter. Most binders have the same number of rings as perforations but this is not required as the rings may fit in alternate or spaced perforations and either in pairs or uniformly spaced.

Each ring is usually in two parts and so mounted that each part thereof is movable in opening and closing. Usually some means is provided to facilitate the opening or closing of the parts of each ring. No practical, inexpensive binder has been provided heretofore, to my knowledge, for holding relatively thin packs of sheets as, for example, one-quarter inch or one-half inch, and which may be opened and closed readily for individual removal of particular sheets in the pack.

One object of this invention is to overcome the objections heretofore encountered in looseleaf binders and to provide an inexpensive binder which may, if desired, accommodate a relatively small capacity.

Another object of the invention is to improve the construction of ring binders to permit separate sheets to be withdrawn or inserted without removing all of the sheets.

Still another object of the invention is to provide in a ring binder for movement of one set of ring segments while the other set of ring segments remain fixed in position so that the former may be opened to facilitate insertion or removal of sheets and wherein the segments do not meet in the center, but have alternate off-center meeting points so as to retain the sheets against disengagement with the ring segments during the insertion or removal of individual sheets.

These objects may be accomplished, according to one embodiment of the invention, by providing a base plate having two sets of ring segments spaced at intervals along the respective opposite edges thereof and coacting to form rings so as to receive looseleaf sheets through punched holes in the sheets. The ring segments on one edge of the base plate are fixed thereto and may be formed integral with the plate when made of plastic or other suitable formable material. The ring segments at the opposite edge are connected together in a series capable of swinging motion as, for example, being attached to a rotatable rod or shaft that extends through a bearing portion of the base plate and having means connected with the shaft for manipulating the latter for opening and closing the segments at this side with respect to the segments of the opposite side of the base plate.

To accommodate punched sheets, the rings may be arranged in pairs or uniformly spaced. While the spacing of the rings is optional, it is preferred that the rings be arranged in pairs, either adjacent to each other or separated, with the pairs of rings spaced along the length of the base of the binder. Preferably, the rings meet off-center so that the sheets will be retained on the fixed or immovable segments of the rings when the movable segments are opened with respect thereto, thus preventing dislodgement of the sheets from all of the rings and effectively maintaining the sheets in place even when the binder is open.

2

This embodiment of the invention is illustrated in the accompanying drawings, in which:

FIG. 1 is a perspective view showing the back portion of the binder having the sheet retaining means according to this invention;

FIG. 2 is a partial top plan view thereof;

FIG. 3 is an end elevation thereof, with the rings closed;

FIG. 4 is a similar view showing the rings open;

FIG. 5 is a cross section through the back portion of the binder on the line 5—5 in FIG. 1; and

FIG. 6 is an end elevation showing a modification of the binder.

The invention is illustrated in the drawings as applied to a binder having covers 1 made of suitable flexible or rigid material, as desired. The covers 1 may be made in one piece and extend continuously across the base of the binder, as desired. A base plate is indicated at 2 and extends transversely of the covers 1 substantially throughout the width thereof. The base plate 2 may be secured in any suitable manner to the covers 1 as, for example, by fastenings, such as rivets 3 extending through the base plate at desired points along the length thereof and through the sheet forming the covers 1.

At one edge, the base plate 2 is provided with an upturned flange 4 extending along the length thereof, while the opposite edge of the base plate 2 is also bent up and back upon itself to form an inverted U-shaped channel 5 extending along the length of the base plate 2. A rod or shaft 6 is housed within the channel 5 and rotatable with respect thereto. The channel 5 thus forms a bearing support for the rod or shaft 6.

The base plate forms a support for rings which are spaced along the length of the base plate. Each of the rings is formed in two segments, a fixed segment being secured in any suitable manner in rigid relation to an edge of the base plate 2 as, for example, by being welded to the flange 4 if the base plate be of metal or formed in one piece with the base plate of plastic or other suitable material.

The other ring segment is fixed rigidly to the rod or shaft 6, extending into a notch 7 in the channel 5 for freedom of swinging motion with respect to the latter upon rotation of the rod or shaft 6.

A fixed ring segment is indicated at 8 and a movable ring segment is indicated at 9. The opposed abutting ends of these segments 8 and 9 are adapted to contact each other at the point indicated at 10. It is preferred that the rings be arranged in pairs, with the several pairs spaced adjacent each other or at intervals along the length of the base plate 2.

A second fixed ring segment is shown at 8' and a second movable ring segment is shown at 9' forming the second ring of each pair. The ring segments 8' and 9' abut at their ends at 10'. When the rings are thus disposed in pairs as thus illustrated, it is preferred that the abutting points 10 and 10' be located on opposite sides of the longitudinal center of the sets of rings so that at least some of the fixed segments will project through more than half of the arc of the rings, thus to facilitate the retaining of the sheets against dislocation when the movable segments are opened to insert or remove a particular sheet or set of sheets. The rings disposed in pairs, as described, afford a cam action as the sheets are shifted from one side to another, thereby preventing a sheet from slipping through a gap in the ends of the rings.

The movable segments are opened by rotation of the rod or shaft 6. Where the binder is of relatively small capacity as, for example, when holding from one-quarter inch to one-half inch stack of sheets, the rings should be sufficiently small so that it would not be practical to open the movable segments by grasping and pulling on

the latter. Accordingly, I have provided an arm, indicated at 11, formed on one end of the rod or shaft 6 which, for simplicity, may be an outturned end of the rod or a part connected thereto.

Upon swinging motion of the arm 11, the rod or shaft 5 6 can be rotated to open or close the movable segments of the rings. Provision may be made for holding the arm 11 in one position and thus retain the rings closed. I have illustrated an upstanding post 12 supported by the base plate 2 and which post 12 has a cam face 12' and 10 a notch 13 therein forming a keeper for receiving the arm 11 and thereby retaining the arm in closed position until it is forced out of the notch 13 to move the shaft.

It is often desirable to provide sheet lifters for ring binders, as indicated at 14 in FIG. 6. Where these are 15 to be used to assist in moving the sheets from one side to the other of the binder or when the binder is closed, provision should be made for guiding the sheet lifters.

Such guiding means is illustrated in FIG. 6 as including web partitions 15 extending from side-to-side of the 20 base plate 2 and spaced along the length of the base plate at suitable or desired intervals. As an example, four such web partitions 15 may be employed, being uniformly spaced along the length of the base plate. These web partitions 15 will serve to retain the sheet lifters and 25 assist in movement of the sheets from one side to the other.

The use of the ring binder will be apparent from the foregoing description. It may be made inexpensively, in small sizes to hold one-quarter inch or one-half inch 30 stack of sheets, and preferably not over one inch in thickness. Nevertheless, the sheets can be inserted and removed and transferred from one side to the other without danger of a single sheet slipping out of the binder through the meeting ends of the ring segments. It is economical in construction and may be made of metal, 35 plastic or other suitable material.

While the invention has been illustrated and described in one embodiment, it is recognized that variations and changes may be made therein without departing from 40 the invention set forth in the claim.

I claim:

A ring binder comprising:

an elongated back plate adapted to be secured to a 45 cover;
a plurality of rings extending transversely of the back plate and spaced apart adjacent opposite ends thereof and intermediate the ends thereof adapted to receive perforated sheets thereon to a maximum thickness of about one inch;
each of said rings including a fixed segment of one 50 length and a movable segment of a different length equal to approximately the length of the fixed segments of adjacent rings;
said fixed segments and said movable segments of each 55 ring having abutting ends therebetween with the

fixed segments being secured along one edge of the back plate;
a shaft extending along the opposite edge of the back plate and having the movable segments fixed thereto and extending upright therefrom;
said back plate having an inverted U-shaped channel thereon receiving the shaft substantially throughout the length of the back plate and mounting the shaft against endwise movement and for rotation;
said U-shaped mounting channel having notches through which the movable segments extend, the width of said notches being substantially equal to the thickness of the respective movable segments whereby swinging movement of the movable segments with respect to the back plate upon rotation of the shaft is confined to a plane extending transversely of the back plate through the respective fixed segments;
an integral operator lever connected with an end portion of the shaft spaced from the plurality of rings for rocking the shaft to open and close the movable segments;
an upright post on the back plate having a cam face extending downwardly from the upper end thereof and a notch immediately below said cam face in position for engagement by the lever for releasably holding the lever in said notch in an oblique position relative to the back plate when the ends of the ring segments of each ring are in abutment with the end of the lever at an elevation approximately equal to the height of the top of the rings so as to provide a handle for leverage; and
upright web partitions extending transversely of the back plate, said partitions extending upwardly from the back plate with their upper edges at an elevation equal to the height of said inverted U-shaped channel and forming sheet lifters thereon.
